(57) CLAIM

The ornamental design for a dog tie out stake as shown and described.

DESCRIPTION

FIG. 1 is a front perspective view of a dog tie out stake, showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines in the figures are for the purposes of illustrating portions of the dog tie out stake, which form no part of the claimed design.
